UNITED STATES PATENT OFFICE.

STEPHEN DUDLEY FIELD, OF YONKERS, NEW YORK.

ELECTRIC LOCOMOTOR.

SPECIFICATION forming part of Letters Patent No. 380,879, dated April 10, 1888.

Application filed December 9, 1886. Serial No. 221,064. (No model.)

To all whom it may concern:

Be it known that I, STEPHEN DUDLEY FIELD, a citizen of the United States, residing in Yonkers, in the county of Westchester and State of New York, have invented certain new and useful Improvements in Electric Locomotors, of which the following is a specification.

The invention relates to the propulsion of vehicles by means of electricity. It comprises certain improvements in the construction of electric motors, the adaptation of the same to moving vehicles, the method of mounting the same upon the vehicles, the manner of connecting the armature with the driving-wheels of the vehicles, the devices for supplying currents thereto, and the devices for regulating and controlling the current supplied to the motor.

The general construction of the electric locomotive may be briefly described as follows: The field-magnet of a suitable electric motor is supported through yielding springs from the axles of the wheels of a truck, and the armature is coupled with the wheels by rigid connecting-rods attached to suitable crank-pins. The rotary motion of the armature is communicated through these connecting-rods to the wheels of the truck. The body of the car or vehicle is supported upon the truck by means of a turn-table resting upon the field-magnet and a frame supported upon suitable springs from the field-magnets and axles. The currents are supplied to the motor from a stationary generator, either through one of the ordinary rails of the track or from an independent parallel rail or conductor especially provided for that purpose. The connections between the vehicle and the rail or other supply-conductor are made through a contact wheel or roller revolving in a plane oblique to the direction of motion of the vehicle for the purpose of securing a reliable electrical connection, as hereinafter shown. The electric currents are led from this contact-wheel through the necessary adjustable resistances and circuit-controlling devices to the motor proper. The resistances and circuit-controlling devices referred to serve to modify the speed rotation of the armature of the motor as well as the direction of its movement. A supplementary electric motor is employed, when required, for actuating the circuit-controlling

devices. It serves to automatically adjust the position of the commutator and the brushes with reference to each other both for the purpose of varying the speed of the motor and reversing its direction. It also performs the office of maintaining the commutator-brushes in such position with reference to the neutral line of the commutator as to cause the current to be supplied with a trifling loss of energy and entire freedom from sparking and burning. The circuit and current controlling devices and the switch-locking mechanism are not, however, fully claimed herein, as it is proposed to make them the subject-matter of another application for Letters Patent.

The invention also comprises many details of construction and organization, which will be hereinafter described in connection with the accompanying drawings, forming part of this specification.

Referring to the drawings, Figure 1 is a plan of the motor as applied to the wheels of a railway-truck; and Fig. 2 is a side elevation of the same, partly in section. Fig. 3 is an end view of the motor, also partly in section. Fig. 4 is a detail view of the commutator and its controlling devices, and Fig. 5 is a section of the same. Fig. 6 shows in diagram the circuit-connections of the apparatus, and Fig. 7 is a detail drawing of the current reversing and controlling device. Fig. 8 is a detail of the armature. Fig. 9 illustrates a modification in the organization of the circuits and controlling apparatus.

Referring to the figures, A' A² represent the two axles of the truck of a railway-motor. These axles are provided with wheels a' a² and a³ a⁴, respectively. The field-magnet of the motor is mounted upon the axles A' A² by means of yielding springs, as represented at B³. The field-magnet here shown consists of two cores, B' B², put together so as to form consequent poles, and respectively extending above and below the armature C. The axle-springs B³ are preferably inserted in boxes B⁴ at the ends of the field-magnet cores and rest upon brasses B⁵, which are fitted to receive the journals of the axles. A sliding lynch-block, B⁶, holds the parts in position with reference to each other. Sufficient room is allowed in the boxes B⁴ for the brasses B⁵ to slide up and down and prevent sudden shocks

upon the motor from the movements of the axles.

For the purpose of obviating the production in the armature of Foucault or other extraneous currents it is preferred to construct the same of a considerable number of soft-iron rings or annular disks separated from each other by thin sheets of paper and glue. These rings or disks are held together by the wire enveloping the armature, no bolts or other conducting materials being employed for the purpose. In an armature constructed in this manner the unequal expansion of the copper and iron under the influence of the heat developed in the armature when running tends to loosen the separate parts of the same. To avoid this, sheets or disks of some other metal—such, for instance, as zinc—are interspersed with the iron disks. These are arranged in such proportion and order as to give to the entire armature-core a total co-efficient of expansion equal to that of the copper wire. The armature is wound in any well-known or desired manner, and is adapted to revolve within a chamber formed between the poles of the field-magnet, the electrical connection and relation between the field-magnet and the armature being preferably of the same character as in the case of a dynamo-electric generator—that is to say, they are connected either in series with each other or the one in a shunt upon the other, as required under different conditions. The coils C of the armature are preferably wound through the interior of the hollow iron core and over its external surface from end to end. The shaft C² of the armature extends within the opening through the disks and is firmly secured in a central position. It is preferred to surround the shaft by a brass collet, C³, upon which there is placed a wooden sleeve or cylinder, C⁴. This is secured by disks C⁵ at the ends of the collet. Four plates of wood, C⁶ C⁶, having their outer surfaces curved to the inner surface of the armature-coils, are placed within the armature next the wire. These widen toward the center and are bound in position by wedges C⁷ C⁷, bearing against the sleeve C⁴. The brass collet is keyed to the shaft by wedge-shaped keys C⁸, which are of advantage in centering the armature.

The field-magnet is constructed with a spider having arms b', b², b³, and b⁴ at one end converging to form a bearing, c', for that end of the armature-shaft. The other end of the field-magnet is provided with a similar spider, forming a bearing, c², for the other end of the armature-shaft. These spiders are preferably bolted to the ends of the field-magnets in the manner shown, as this forms a convenient mechanical construction and one which gives a solid support for the revolving armature. The journals or bearings are designed to be fitted in any well-known manner for convenience of lubrication and for compensating for the wear.

Upon the respective ends of the armature-

shaft C² are fixed cranks D' and D². These are designed to take hold of connecting-rods d' d² and d³ d⁴, respectively. The connecting-rods d' and d² couple the crank D' with the two wheels a' and a² by means of crank-pins e' and e², which may be inserted into the sides of the wheels at suitable distances from their centers. In like manner the rods d³ and d⁴ connect the crank D² with the pins e³ e⁴ of the wheels a² and a⁴. The cranks D' and D² are preferably placed at an angle of ninety degrees to each other, so that there may be no dead-point in the armature with reference to the wheels and that the rotary motion of the armature may be transmitted to the wheels by forces parallel to a line connecting the centers of the driver-wheels.

The crank-arms D' and D² extend into suitable sliding boxes, d⁵, fitted into the connecting-rods at the point between the corresponding pins. These permit the necessary play of the crank during the revolution of the armature, and at the same time permit the parts to adjust themselves for any relative movement between the motor and the axles due to the action of the springs B³.

The body of the vehicle is preferably supported upon a turn-plate or fifth-wheel, F, which is stepped in a bar, F', at the top of the field-magnet at or near its center. The body itself bears upon a frame, F³, which is supported above the axles by means of yielding springs f', f², and f⁴, of any suitable character. These springs rest directly upon the boxes B⁴ of the respective axles and serve to ease the rocking movements of the vehicle with reference to the truck. The frame F³ is provided with curved slots f⁵ and f⁶ for receiving corresponding projections from the body of the vehicle. These bind it thereto, while permitting a sufficient swiveling movement of the truck upon its turn-plate F' in passing a curve.

It will be understood that any of the usual forms of spring-buffers may be employed for preventing jolts and irregular movements of the truck from being communicated to the body of the vehicle.

The electric currents are preferably conveyed to the motor through an insulated contact-rail, G. This may, with advantage, consist of an ordinary track-rail laid along the bed of the road, preferably between and parallel to the two ordinary rails, G' and G², but at a little distance from one of them. This conducting-rail may with advantage be supported upon a plate of insulating material, g, which rests upon a plank, g', laid upon the road-bed, which serves to raise it above the level of the other two rails. In this case the contact devices for collecting the current therefrom are not required to extend downward as low as the supporting-wheels of the truck.

The particular form of contact device which it is preferred to employ consists of a brush-wheel, H, made up of thin plates of brass, steel, or other suitable material (shown at h h)

placed side by side and bound together to form a wheel of sufficient breadth. The edges of these disks or plates possess sufficient resiliency to insure the making of a good electrical contact and to give a certain flexibility to the periphery of the wheel. The contact-wheel is carried in a bearing or yoke, H' , and is set in a vertical plane oblique to the direction of the rail G , so that the movement of the motor will cause it to revolve on its axis, and at the same time to rub angularly upon the surface of the rail.

For the purpose of easily adjusting the position of the brush-wheel H the yoke H' is carried by an arm, h' , mounted in suitable bearings, h^2 h^3 , which permit it to be turned horizontally in one direction or the other for adjustment. An arm, h^4 , extends from the end of the support h' and is provided with a set-nut, h^5 , and bolt h^6 , extending through a quadrant, h^7 . The curve of the quadrant permits the rod h' to turn, and by means of the set bolt and nut it may be securely fastened in any desired position. A spring, h^8 , exerts a force tending to press the rod, and consequently the brush-wheel h , downward against the surface of the rail G to secure an efficient and at the same time an adjustable contact. The nut h^9 , against which this spring presses, is preferably adjustable, and it serves by striking against the bearing h^3 to determine how far the wheel and its support shall be pressed downward. The connections from the contact-wheel H are through a conductor, 1, to an adjustable artificial resistance, R . This resistance is constructed in sections $r' r^2 r^3$, &c., with connecting-plates $s' s^2 s^3$, &c. A contact-brush, R' , is movable along the plates for the purpose of including more or less of the sections $r' r^2 r^3$, &c., in circuit. The last plate, s^{10} , of these series is not connected with the resistance, and hence when the brush R' rests upon it the circuit is interrupted. The brush R' is carried upon a nut, J , movable along a screw-threaded rod, J' . This rod, when turned in one direction, carries the nut, and thus the brush R' , to one end of the resistance R . When rotated in the opposite direction, it moves the brush R' toward the opposite end of the resistance R .

For the purpose of conveniently turning the rod J' as desired it is connected by bevel-gear $i' i^2$ with a rod, i^3 , which is provided with a hand-wheel, i^4 , of any suitable character. By turning this wheel in one direction or the other the position of the brush R' may be varied and the current which will be delivered through the brush correspondingly regulated, according to the amount of resistance interposed in the circuit. From the contact-brush R' the current traverses a conductor, 2, to one plate, K' , of a circuit-controlling device, K . A second plate, K^2 , of the same device is connected by a conductor, 3, with one terminal of the field-magnet coils of the motor. A conductor, 4, connects the other terminal of the field-magnet coils with a contact-brush, N , bearing against

one of the axles of the truck, which thus completes the circuit with the rails G' and G^2 of the main track.

The circuit-changer proper, K , is applied to four contact-points, k' , k^2 , k^3 , and k^4 . These combined with the circuit-changer K form a circuit-controller for the armature of the motor. The plates k' and k^2 are united by a conductor, 5, and also by a conductor, 6, with the brush N' of the armature. The contact-plates k^3 and k^4 are united by a conductor, 7, and by a conductor, 8, are connected with the terminal brush N^2 of the armature. The plate K may be shifted so as to bring it in contact either with the plates k' and k^3 or with the plates k^2 and k^4 , as desired. When in the position shown in the drawings, the current passes in one direction through the armature-coils and a shunt from this circuit includes the field-magnet coil. When the position of the plate K is reversed, the direction of the current through the motor-armature will also be reversed, although the direction through the field-magnet coils will remain unchanged.

For the purpose of conveniently controlling the position of the reversing plate K a rod, o , couples the plate with a hand-lever, O .

As it is undesirable for many reasons to reverse the connections when the motor is under the influence of a strong current, it is preferred that the lever O should be movable only when either a very large amount of the resistance R is in circuit or else when the circuit is completely interrupted by the contact of the brush R' with the plate s^{10} . The lever O is therefore placed in such position with reference to the brake-wheel i^5 that an arm, o' , is locked by a flange, o^3 , on picking-up wheel, i^5 , except when the brush R' is in a predetermined position. The flange o^3 is carried upon a wheel, o^4 , gearing with a pinion, o^5 , upon the rod i^5 . The flange o^3 has an opening, o^6 , through which an arm, o' , upon the lever O may pass freely when the wheel is in its predetermined position for unlocking.

It remains now to describe the connections between the brushes N' and N^2 and the commutator P . This commutator is constructed with a series of contact sections or segments with which the brushes N' and N^2 make contact. The commutator is secured rigidly to the armature-shaft and revolves therewith. The brushes N' and N^2 , however, are mounted upon a ring, S , supported upon suitable friction rollers, S' , which permits it to be revolved upon its axis. The brushes N' and N^2 are affixed to suitable supports, T' and T^2 , which permit them to be inclined in one direction or the other with reference to the neutral axis of the commutator, according to the direction of rotation of the latter. The brushes preferably bear nearly in a perpendicular direction against the surface of the commutator-plates. They are also more or less flexible, being made up of thin plates or wires of good conducting material. The brush-holders N are pivoted in supports T' by means of the pins n' , ex-

tending through slots t . Springs n serve to press the brushes toward the commutator. A projection, n^2 , upon each brush is employed for limiting the movement of which each brush is capable upon its axis n' by contact with two adjustable screws or stops, t' and t^2 , carried in the support T' .

It is well known that at a certain position of the commutator with reference to the armature, known as the "neutral axis," there will be less sparking than at any other point, and it is usually desirable to maintain the contact of the brushes at such points. For this reason it has been customary usually to adjust the brushes by hand. It may be done automatically, however, in the following manner: A subsidiary motor, U , acts to adjust the position of the ring S , and thus of the brushes N' and N^2 . To this end the field-magnet u' of the motor U is included in a shunt-circuit from the brushes N' and N^2 by conductors 10 and 11, extending from the conductors 8 and 6. The armature of this motor, however, is included in a separate circuit derived from contact-brushes V' and V^2 , applied to the commutator. These brushes are constructed much in the manner of the brushes N' and N^2 , and are preferably placed at points ninety degrees therefrom. They may, however, be placed in other positions, the essential feature being that they be at points of equal and like potential. The plates of the commutator are, as hereinafter pointed out, numbered to make it more easy to locate the brushes. Provided the brushes N' and N^2 are at the points of highest efficiency upon the commutator, the brushes V' and V^2 will then be at points of equal potential. If, however, the brushes N' and N^2 should be at other points than the points of highest efficiency, a certain difference of potential will exist between the brushes V' and V^2 , and a corresponding current will be delivered through the conductors 12 and 13, connected therewith, to the armature u of the subsidiary motor U . This will cause the armature u to revolve, and the shaft u' extended therefrom will revolve in a corresponding direction. This shaft carries a worm gearing with teeth upon the wheel or ring S , and thus by the revolution of the armature of the motor the brushes N' and N^2 will be adjusted in the direction required to place them at the proper points with reference to the commutator, it being understood that the connections through the armature of the motor U are such as to cause it to revolve in the proper direction to place the brushes V' and V^2 at the points of equal potential upon the commutator. The supplementary brushes V' and V^2 are not placed, it should be observed, in contact with the same segments of the commutator as the brushes N' and N^2 , but are arranged to make contact only with, for instance, every third or fourth segment. This result is secured in a convenient manner by longitudinally extending certain of the contact-plates, as desired, beyond the others, as shown at w

w in Fig. 5. The intermediate contact-plates are shorter and come beneath the brushes N' and N^2 only. The spaces between the extended plates are, however, preferably filled by short plates of the same material for the purpose of causing an even wear upon the surfaces of the commutator. The individual commutator-plates are preferably numbered or otherwise arbitrarily designated. This renders it easy to determine by inspection which are diametrically opposed and which are separated by an angle of ninety degrees.

In Fig. 9 a modification is illustrated in which a different organization of circuits for the motor is adapted. In this figure the conductor 1, leading from the contact-wheel H , passes through an adjustable resistance, R , of a character presently to be described, thence to the field-magnets of the motor and through a circuit-reversing device, K , for the armature. From the armature the connections are continued to the return-conductor by the car-wheels. The reversing device consists of four contact-points, $k' k^2 k^3 k^4$, to which two circuit-closing points, $K' K^2$, carried by an arm, o , are applied. The arm o is coupled to a wheel, u' , geared to the shaft u^2 of the supplementary motor U , by means of which the commutator-brushes V' and V^2 are regulated. By continuing the revolution of the supplementary motor the circuit-reversing plates K' and K^2 may be carried from one pair to the other of the contact-plates, thus reversing the circuit through the armature. The revolution of the shaft of the supplementary motor will at the same time act through its gearing with the commutator-ring S to reverse the position of the brushes of the commutator. As it is necessary, however, that the reversals should not take place when too strong a current is traversing the armature of the motor, it is preferred to interrupt the connections of the armature during the time of the reversal. For this purpose the arm o of the reversing device extends loosely through the support for the plates, and two adjustable nuts, o^6 and o^7 , determine the play which it shall have. By means of these nuts the circuit-closing plates may be drawn from one pair of contact-plates at the proper moment, and sufficient time will elapse before they are placed in contact with the other pair to allow the commutator-brushes to be adjusted to approximately their proper positions before the circuit of the armature is again completed.

For the purpose of more readily controlling the supplemental motor its field-magnet is included in a shunt-circuit, as before, while the armature is included in a circuit controlled by means of a switch device, Y . This consists of a lever, y , having two circuit-closing plates, y' and y^2 , insulated from each other and respectively connected with the contact-brushes V' and V^2 , and provided with six contact surfaces or plates, $z' z^2 z^3 z^4 z^5 z^6$. Two of these, z' and z^2 , are respectively connected with the brushes V' and V^2 , applied to the ar-

mature. When the lever stands in the position shown in the drawings, then the circuit is completed, as before, through the armature of the supplemental motor. When it is moved 5 into contact with the plates z^3 and z^4 , it serves to drive the supplemental motor in one direction, and when moved into contact with the plates z^5 and z^6 it drives the supplemental motor in the opposite direction. For this purpose the two plates z^3 and z^4 are respectively connected with the conductor 4 through a resistance, R^2 , and with the conductor 1. The plates z^5 and z^6 are respectively connected with the plates z^3 and z^4 .

15 Instead of employing the supplementary motor for adjusting the position of the commutator-wheel S, it may be, in some instances, desired to employ a mechanical device of any suitable character which is liberated by an 20 electro-magnetic device.

An adjustable resistance, R , in the line 1 is preferably so constructed that successive portions may be introduced in multiple arc instead of in series. This is desired for the purpose of avoiding the necessity of employing 25 resistance-conductors of sufficient size to convey the entire current required for the motor. The resistances are inserted one after another by means of a cam device. (Illustrated in Fig. 30 10.)

The device which it is preferred to employ for cutting the resistances $r' r^2 r^3$, &c., in and out of circuit consists of a shaft, q , which may be turned in one direction or the other by 35 a proper system of gearing. This shaft carries a non-conducting section of a cylinder, q' , and a conducting-segment of a cylinder, q^2 , the surfaces of which are normally in the same cylindrical surface. The segment q^2 is supported upon two hinges, $q^3 q^4$. A series of 40 conducting-springs, $v' v^2 v^3$, &c., are designed to be released in succession from this segment as it is turned toward the right hand. For this purpose the segment q^2 may be of gradually-decreasing width, as represented, and the 45 ends of the springs arranged in a straight line, or the springs may be laid in a spiral direction as regards the surface of the cylinder-segment, while the edge of the plate or segment 50 q^2 is straight. In the form represented the segment widens from one end to the other by steps or ledges corresponding to the respective springs. It is desired that the interruptions of the circuit should be quick and sudden and not gradual when the several resistances $r' r^2$, &c., are to be cut out of circuit. 55 For this reason the segment q^2 is coupled to the shaft q by a pivoted elbow, $q^4 q^5$. The arm q^4 is rigidly secured to the shaft, while the arm q^5 links the edge of the segment q^2 with the arm 60 q^4 . When the shaft is revolved toward the right hand, the elbow $q^4 q^5$ tends to straighten, thus throwing the circuit-interrupting edge of the segment q^2 outward from the shaft, and 65 subsequently causing it to follow the movement of the shaft toward the right hand, thus interrupting the connections one after another

by allowing the springs to fall over the edge of the segment against the non-conducting surface of the section q' of the cylinder. When 70 it is desired to replace the resistances, it is evident that the segment q^2 must first be brought down to its original position—that is to say, into the cylindrical surface of the section q' —so that the springs may slide upon its surface. 75 To accomplish this the elbow closes and draws the edge of the segment q^2 down behind the edge of the cylinder-section, thus allowing the springs to pass readily into contact with the conducting-segment q^2 , as required. The conducting-segment q^2 is connected with conductor 1, while the levers or springs $v' v^2$, &c., are respectively connected through the resistance-coils $r' r^2 r^3$, &c., with the conductor 2, leading to the field-magnet. When the several levers are in contact, the several resistances are included in multiple arc. When it is desired to increase the resistance, the coils $r' r^2 r^3$ are successively cut out of circuit by 80 turning the cam-cylinder and causing the levers to drop suddenly from the conducting-surfaces. 85

In constructing the resistance it is designed that the coils be so made that the sum of their conductivities shall equal the conductivity of 90 the main line or the conductivity of the conductors leading through the motor, and thus they will be individually of much less conductivity than would be required if they were placed in circuit in series. 95

I claim as my invention—

1. The combination, with a car-truck, of an electric motor supported between the axles of said truck, a crank-arm upon the shaft of said motor, a coupling-bar having a sliding connection with said crank-arm, and a crank-pin upon one of the wheels of said truck coupled with said connecting-bar. 105

2. The combination, substantially as hereinbefore set forth, with the armature of an electric motor, of a crank-arm at one end thereof, two wheels of a vehicle, a link connecting the same, and a vertically-sliding connection between said crank-arm and said link. 110

3. The combination, with the wheels of a vehicle and their axles, of an electric motor mounted upon said axles, intervening springs permitting slight relative movements between the axles and the motor, linked connections between the wheels upon each side of the vehicle, crank-arms carried upon the shaft of the motor, and vertically-yielding connections between said crank-arms and the linked connections. 115

4. The combination, with the driving-wheels of a vehicle, of crank-pins upon the same, a horizontal link connecting the crank-pins, an electric motor mounted upon the axles of said wheels, having its axis in the plane of the axes of the driving-wheels, a crank upon the shaft 120 of the motor, and a vertically-yielding connection between the crank and said link. 130

5. The combination, with the wheels of a vehicle, of crank-pins carried thereby, links

- connecting the crank-pins of the wheels upon each side of the vehicle, an electric motor carried upon the axes of said wheels and having the axis of its armature in the plane of the axes of said wheels, a crank at each end of the armature axis, said cranks being set at an angle with reference to each other, and vertically-yielding connections between the cranks and the respective links.
10. 6. An electric motor, in combination with a truck between the axles of which it is supported, and a vehicle supported upon said motor.
15. 7. In an electric locomotive, the combination, with the armature and the field-magnets, of the axles of the locomotive, the boxes at the ends of the field-magnets, into which said axles extend, bearing-blocks for said axles, and yielding springs between said blocks and 20 the upper portions of said boxes.
25. 8. The combination, with an electric motor, of two pairs of wheels and their respective axles, the body of a car, a turn-table supported on the motor, through which said car bears 30 upon said electric motor, and a yielding support between said body and said axles.
35. 9. In an electric machine, an armature-core composed of insulated plates of soft iron and interposed zinc plates, substantially as described.
40. 10. In an electric machine, an armature consisting of a core composed of plates of soft iron separated from each other, with plates of zinc interspersed therewith, and bobbins of insulated wire binding the plates together, substantially as described.
45. 11. The combination, with an electric motor, of a contact-wheel adjustable in an angular direction from the line of travel, a spring tending to force the wheel downward, an adjustable stop for limiting the downward thrust, and a quadrant and arm applied thereto for regulating the angular position of the contact-wheel.
50. 12. The combination, substantially as hereinbefore set forth, with an electric motor, of conductors for supplying currents thereto, a

device for controlling said motor, a second electric motor for controlling said device, having its field-magnets included in a shunt upon 50 the armature of the motor, and a circuit including the armature of the second motor derived from approximately the neutral points of the armature of the first motor.

13. In an electric machine, a commutator 55 composed of insulated segments of different lengths, certain of which segments extend across the width of the commutator, while others are insulated at certain predetermined points.

14. The combination, with the armature of an electric motor, of a commutator having certain of the commutating-plates extended beyond the others, a pair of brushes applied to the commutator, and a second pair of contact-brushes applied to the extended plates, substantially as described.

15. An electric circuit-controller consisting of a series of contact-springs, a contact-surface in the form of a segment of a cylinder, a 70 shaft upon which it is loosely mounted, a knee-joint connecting the same with the shaft, whereby one edge may be thrown a greater or less distance from the shaft, and a non-conducting striking-surface for the spring.

16. A circuit-controlling device consisting of a series of contact-springs, a contact-plate movable in one direction or the other beneath the springs, means for forcing the plates against the pressure of the springs when it is to be 80 moved in a direction for releasing the latter and for forcing it in the opposite direction when it is to be passed beneath the springs, and a non-conducting bearing-surface for said springs when they are released from the contact-plate.

In testimony whereof I have hereunto subscribed my name this 23d day of November, A. D. 1886.

STEPHEN DUDLEY FIELD.
